UNITED STATES PATENT OFFICE.

JOHN GRIFFIN, OF YONKERS, NEW YORK.

HORSESHOE ATTACHMENT.

SPECIFICATION forming part of Letters Patent No. 760,785, dated May 24, 1904.

Application filed October 21, 1902. Serial No. 128,143. (No model.)

To all whom it may concern:

Be it known that I, JOHN GRIFFIN, a citizen of the United States, residing at Yonkers, in the county of Westchester and State of New York, have invented certain new and useful Improvements in Horseshoe Attachments, of which the following is a full and complete specification, such as will enable those skilled in the art to which it appertains to make and use the same.

The object of this invention is to provide an improved attachment for horseshoes whereby a plate-shoe may be provided with calks whenever desired and whereby a sharp shoe may also be provided with calks when the latter are worn off or worn smooth; and with these and other objects in view the invention consists in an attachment for horseshoes constructed as hereinafter described and claimed.

The invention is fully disclosed in the following specification, of which the accompanying drawings form a part, in which the separate parts of my improvement are designated by suitable reference characters in each of the views, and in which—

Figure 1 is a top plan view of a horseshoe provided with my improved attachment; Fig. 2, a bottom plan view thereof, and Fig. 3 a longitudinal central section of the attachment removed from a shoe.

In the drawings forming part of this specification I have shown at *a* an ordinary horseshoe provided with a toe-calk *a*² and heel-calks *a*³, and in the practice of my invention I provide an attachment which comprises a main block *b*, provided with a yoke-shaped top plate *c*, having forwardly-directed side or end members *c*², which are adapted to be inserted between the toe portion of the shoe and the horse's foot. The block *b* is also provided with a yoke-shaped bottom plate *d*, having forwardly-directed end members *d*², provided with toe-calks *d*³, and the forwardly-directed end member *d*² of the yoke-shaped plate *d* rests on the bottom of the shoe at the opposite sides of the calk *a*² when the attachment is in position.

Passing centrally through the block *b* is a screw *e*, the front end of which is provided with a head or stationary nut *e*², which may

be secured thereon after the screw is passed through the block *b*, and rearwardly of the block *b* the said screw *e* is also provided with a nut *e*³, and that portion of the screw which passes through the block *b* is not threaded. 55

Mounted on the screw *e* rearwardly of the nut *e*³ is a screw-threaded collar *f*, having side wings *f*², to which are pivoted links or levers *g*, which are also pivoted at *g*² to the free ends of arms *h*, which are pivoted between the plates *c* and *d* at *h*² adjacent to the opposite sides of the block *b*. 60

The free ends of the arms *h* when the attachment is in position overlap the bottom portions of the sides of the shoe adjacent to 65 the ends thereof, as clearly shown in the drawings, and said arms are provided with flat fingers *h*³, which when the shoe is in position overlap the top portion of the shoe, and the heel portions of the arms *h* are provided 70 with calks *h*⁴, which are shown in dotted lines in Fig. 1 and in full lines in Figs. 2 and 3.

It will be understood that in practice my improved attachment may be applied to a horseshoe while the shoe is on the foot, and 75 in doing this the forwardly-directed members *c*² of the plate *c* are slipped between the forward part of the shoe and the hoof and the attachment or the arms thereof are pressed down between the sides of the shoe. A 80 wrench is then applied to the nut *e*³ and the screw *e* is turned, so as to force the free ends of the arms *h* outwardly, and in this operation said ends of said arms pass beneath the shoe, and the finger-pieces *h*³ thereof pass 85 between the shoe and the horse's foot, and the attachment is securely locked to the shoe.

This device is simple in construction and operation and perfectly adapted to accomplish the result for which it is intended, and I 90 reserve the right to make all such alterations thereof as fairly come within the scope of the invention.

Having fully described my invention, what I claim as new, and desire to secure by Letters 95 Patent, is—

An attachment for horseshoes comprising a block having yoke-shaped top and bottom plates adapted to fit above and below the front portion of the shoe, the end portions of the 100

bottom plate being provided with calks, a screw passed through said block and free to turn therein and provided with collars or nuts forwardly and backwardly of said block, arms 5 pivoted at the opposite side of said block and adapted to rest on the bottom heel portions of the sides of the shoe and provided with finger-pieces which overlap said sides, a screw-threaded collar mounted on said screw rearwardly of said block, and links pivoted at the opposite sides of said collar and to the rear 10

portion of said arms, substantially as shown and described.

In testimony that I claim the foregoing as my invention I have signed my name, in presence of the subscribing witnesses, this 20th day of October, 1902. 15

JOHN GRIFFIN.
